THUMB INDEX FOR BOOKS AND THE LIKE

Karl L. Schiff, Philadelphia, Pa.

Application June 11, 1952, Serial No. 292,888

4 Claims. (Cl. 283—42)

The invention relates to a thumb index for books or the like, that is to an alphabetical, numerical or other index having the indicia at the ends of notches which are cut into the free margins of the book pages.

The object of the invention is an improved relative arrangement of such notches and/or arrangement of the indicia on the notches so as to facilitate finding a desired section.

The known thumb indexes have either all indicia facing in the same direction or in one part of the book, for instance the first half, they face in one direction and in other part, for instance the second half, they face in the other direction.

The shortcomings of these known arrangements are that with the book open or on its front, certain ones or all of the indicia face away from the onlooker so as to require for their detection the turning over of the book entirely or in part.

So as to overcome this disadvantage, many books, especially dictionaries, have printed along the index margin of each page the location of the indicia which, when the book is open, face away from the onlooker. This system not only means a great amount of careful printing so that the marginal printed indicia line up with the thumb indicia, but it is also unsatisfactory insofar as the margins of the pages change their relative positions, thereby largely defeating the purpose of this known system.

The invention overcomes the shortcomings of the known indexes by alternating the direction in which successive notches and their indicia face so that for instance one notch faces toward the front, the notches flanking it face toward the back, and so on.

It is not necessary, and sometimes not desirable, to carry this scheme through from one end of the index to the other. At the front and the rear of the book, or for a series of sections each having only relatively few pages, a few adjacent notches and indicia, say two or three, may face in the same direction.

The new index will permit the easy finding of any letter, number or the like at whatever page the book may be open. If a letter or numeral does not face the reader, he will still find it without effort as being located between the exposed, immediately preceding and following letters or numbers.

A further feature of the invention consists in the arrangement in pairs of successive, oppositely facing notches so that the two notches of one pair register fully or in part. This results in a shortening of the total length of the index and often will permit the location of all indicia in one continuous, double row where two successive rows would customarily be required.

The indicia facing in one direction may show in easily distinguishable form, such as by smaller type or different color, the next adjacent indicia facing in the opposite direction, thereby facilitating still further the use of the index. This would also allow the application of the invention for indicia having no well known sequence.

2

The use of the novel index may also be facilitated by providing on the conical surfaces of the notches, that is on the free edges of the pages, duplicates of the respective indicia found at the ends of the notches.

5 Several embodiments of the invention are illustrated in the attached drawing, in which:

Figure 1 is a perspective of an open book provided with one form of the novel alphabetical index;

10 Figure 2 is an end elevation of the book shown in Figure 1, in closed position;

Figure 3 is an end elevation similar to Figure 2, illustrating a second embodiment;

15 Figures 4 and 5 are larger-scale fragmentary perspective views seen from the lines 4—4 and 5—5, respectively, of Figure 3 and in the direction of the arrows thereon;

Figure 6 is a fragmentary elevation similar to part of Figures 2 and 3, illustrating a third embodiment; and

20 Figure 7 is a larger-scale fragmentary perspective view seen from line 7—7 of Figure 6 and in the direction of the arrows thereon.

The books illustrated in the drawings have a front cover 3, a back cover 4 and pages 5. The pages have free margins 6.

The book shown in Figures 1 and 2 has cut into the 25 free margins 6 generally conical or similarly shaped recesses or notches 7 and 8, at the ends of which are the indicia 9 and 10 respectively. There is one notch for each letter of the alphabet. The notches 7 face toward the front cover 3 and their indicia 9 toward the back cover 4, while the notches 8 face toward the back cover 4 and their indicia toward the front cover 3. The notches 7 for the first three letters of the alphabet—A, B, and C—face in one direction and the last three notches 8 for the last three letters—X, Y, and Z—all face in the opposite direction. The notches 7 and 8 for the letters D to V between the aforesaid notches for the end letters A, B, C and X, Y, Z, respectively, alternate in direction.

With the book opened, for instance, as shown in Figure 1 at the letter K, it is easy to find any other letter 40 without having to turn the book over. About half of all the letters are visible because they face the onlooker, and any letter not facing the onlooker is found without effort because it must be at the notch between the adjacent visible letters. For instance, notch 8 for letter 45 D is, of course, between the two adjacent visible indicia 9 for the letters C and E.

While Figure 1 shows the arrangement of the notches 7, 8 in two sequential rows, Figures 3 to 5 illustrate a modified arrangement in which the corresponding 50 notches 107, 108 of adjacent indicia 109, 110 are arranged in pairs in one double row, and in which the two notches of each pair register approximately in plan view, that is both have the same distances from the upper and lower margins of the pages.

55 Figures 4 and 5 show at the bottom of each notch in large type the letter of the alphabet relating to the respective notch, whereas the letter of the registering notch is shown in smaller type. This might be compared to the inscriptions on the keys of typewriters with upper and lower case letters or signs.

The embodiment illustrated in Figures 6 and 7 differs 60 from the preceding embodiment by a partial registering only of pairs of successive letters, so that a continuous index row is obtained. In this case, the letter appearing at the bottom or end of each notch 207, 208 is repeated at 11 on the inside of each notch. This last-named feature permits easy selection of a notch the letter at the bottom of which faces away from the reader.

The same system, applied in the illustrated embodiments to an alphabetical index, may be applied to a numerical index or to any other index in which the sequence of the indicia is known as a matter of course.

The invention as illustrated and described is susceptible of further modifications and adaptations. For instance: the number of the indicia facing in the same direction at the ends of a book or the like may be varied; the direction in which the indicia face need not alternate for each single letter or number but throughout or at certain parts of a book, a few adjacent indicia may face in one direction if doing so should be found desirable for one reason or another; and the different disclosed features may be employed separately or in different combinations.

What is claimed is:

1. Thumb index for a book and the like composed of a multitude of stacked sheets; notches cutting transversely to said sheets into and extending part way across one free margin of said book and the like, and each notch providing an indicia-bearing end face; at least some of said notches being arranged in a row extending generally at an angle across at least part of said free margin; adjacent notches in said row having their said end faces oppositely directed, extending into different parts of said edge, and being of a length providing good visibility of their said indicia-bearing end faces, so that in any open position of said book and the like certain ones of said indicia-bearing end faces are turned toward and the others away from an onlooker thereby permitting the 25 convenient locating of all indicia.

2. Thumb index according to claim 1 having several successive ones of said indicia-bearing end faces of said notches near one end of a book and the like turned in the same direction away from said end while the said 5 end faces adjoining toward the middle of said book and the like alternate in direction.
3. Thumb index according to claim 1 having adjacent notches, when viewed vertically to said sheets, overlap each other at least partly and extend in opposite directions away from their respective indicia-bearing end faces.
4. Thumb index according to claim 1 having at least certain ones of said notches arranged in pairs and extend in opposite directions away from their respective indicia-bearing end faces, the notches of such pairs registering 10 with each other when viewed vertically to the pages of the book.
